UNITED STATES PATENT OFFICE.

FRANKLIN SCHNEIDER, OF CLEVELAND, OHIO, ASSIGNEE TO THE VAN DORN AND DUTTON COMPANY, OF CLEVELAND, OHIO, A CORPORATION OF OHIO.

ELECTRIC SWITCH.

1,073,935.

Specification of Letters Patent. Patented Sept. 23, 1913.

Application filed February 13, 1911. Serial No. 608,331.

To all whom it may concern:

Be it known that I, FRANKLIN SCHNEIDER, a citizen of the United States, and a resident of Cleveland, county of Cuyahoga, and 5 State of Ohio, have invented a new and useful Improvement in Electric Switches, of which the following is a specification, the principle of the invention being herein explained and the best mode in which I have 10 contemplated applying that principle, so as to distinguish it from other inventions.

It is desirable in electrically operated drills and like tools of the portable type, that is, tools designed to be handled and 15 controlled directly by the workman using the same, that the circuit controlling means be so constructed as to admit of convenient operation by the workman without shifting his hands; it is also desirable in tools of 20 this class that means be provided whereby the current is instantly turned off should the tool escape from the operator's control.

The object of the present invention is the provision of a switch and suitable operating 25 means therefor, whereby these several desirable results may be obtained; while at the same time a quick make-and-break of the circuit is also secured under conditions that will effectually prevent arcing with the resultant "freezing" of switch parts, which 30 occasions so much trouble in connection with mechanism of this kind, especially in the hands of unskilled operators.

Said invention, then, consists of the 35 means hereinafter fully described and particularly pointed out in the claims.

The annexed drawings and the following description set forth in detail certain mechanism embodying the invention, such 40 disclosed means constituting, however, but one of various mechanical forms in which the principle of the invention may be used.

In said annexed drawings—Figure 1 is a central longitudinal section of a handle member typical of those found in connection with electrically operated tools and shows within such member my present improved construction of switch, the parts contained in the handle member being 45 shown in elevation for the purpose of clearness, while the handle member is sectioned on the line 1—1; in Fig. 3; Figs. 2 and 3 are respectively transverse sectional views of the same on the lines 2—2 and 3—3, Fig. 1: 50 Fig. 4 is a broken sectional view correspond-

ing with Fig. 2, but showing the parts in a different operative position; Fig. 5 is similarly a broken sectional view corresponding with Fig. 3, but showing the parts in a different operative position; Fig. 6 is a 60 longitudinal central section of a detail on the line 6—6, Fig. 2; Fig. 7 is a plan view of a detail as indicated by the section line 7—7, Fig. 1; Fig. 8 is a central longitudinal section of another form of handle member, 65 showing a similar construction of switch, but in combination with a modified form of mechanism for actuating the same; Fig. 9 is a transverse section of such modified construction taken on the line 9—9, Fig. 8; and 70 Fig. 10 is a section, with certain parts removed, on the line 10—10 in Figs. 3 and 5.

As will be observed in the case of both constructions of switch illustrated in the drawings just described, the switch proper, 75 as well as the actuating mechanism therefor, is designed to be incased, or housed, directly within one of the handle members 1, whereby the tool, whatever its character, is manipulated. The inner end 2 of such handle 80 is enlarged to receive the switch, of which the several operative parts are mounted on a base 3 in the form of a flanged disk of insulating material. The terminals of the circuit controlled by the switch are in the 85 form of disks 4 embedded in such base, so as to lie flush with one face thereof, the opposite ends of the pins 5 that hold such disks in place, constituting binding posts for the attachment of the lead wires 6, as will 90 be readily understood. Mounted in the base adjacent to each such terminal 4, and on its forward side (having regard to the direction of movement presently to be explained), is a block 7 of carbon, preferably 95 also in the form of a disk, such block being recessed at one side of its outer face to receive the overlapping edge of the terminal disk 4 whereby it is secured in the recess designed for its reception in the base. The 100 outer faces of the terminals 4 and the carbon disks 7 are therefore flush with each other and with one face of the base, but the terminals 4 partly cover the carbon disks 7.

Rotatably mounted in the center of the 105 base is a spindle 8 which carries a frame-member 9 that in turn supports the bridge-piece 10 by means of which the terminal disks 4 may be connected when desired. Such bridge-piece, while non-rotatably se- 110

cured to the frame by pins 11, is nevertheless capable of a certain amount of movement longitudinally of the spindle; but is resiliently held against the base and thus 5 against the terminals, when placed in position thereover, by means of springs 12 surrounding said pins and interposed between the frame and said member.

Frame-member 9 is not rigidly secured to 10 the spindle 8, but is connected therewith through the medium of a flat coil spring 13 attached at its inner end to said spindle, and at its outer end to a suitable lug 14 provided for this purpose on the upper face of 15 the member. Rotation of such member is furthermore controlled by means of a catch 15 the construction of which is best illustrated in Figs. 3 and 5. This catch is reciprocally held in two upwardly projecting 20 arms 16 on the member, and has one end adapted to successively engage a series of four pins or lugs 17 mounted in the edge of the flange of the supporting base 3. Said reciprocable catch is normally held in position 25 thus to engage a retaining lug, and is likewise movable out of such position, by means of a cam 18 carried by the spindle and engaging with a shoulder on the reciprocable member, said shoulder being conveniently provided by forming an open bend 30 19 in the catch, as illustrated in figures just referred to. Oppositely disposed from the cam on the spindle is a lug 20, so conformed as to engage with the same bend and lock 35 the spindle against rotation.

As a result of the foregoing construction, the normal position of the parts just described, is that illustrated in Fig. 3, where the lug 20 on the spindle thus locks the latter against rotation, with the catch in engagement with a lug 17 on the base. Upon 40 rotating such spindle, however, in the direction of the arrows appearing on said figure, the effect is to throw the catch out of engagement with said lug, the parts being shown in Fig. 5 as they appear just at the moment of release of the catch from the lug next following the one engaged in Fig. 3. The effect of rotating the spindle, however, 45 through substantially 90 degrees, as is necessary to effect such release of the catch, is to wind up the coil spring 13, which is consequently under tension at the time of release. The frame and parts carried thereby, 50 are accordingly moved instantly, but inasmuch as the spindle remains stationary, the effect of such movement is again to throw out the catch 15, so that it will engage with the next succeeding stop lug 17. The operation 55 may then be repeated, and so the switch caused to successively assume a position in which the terminals are bridged, or connected, and one in which they are disconnected, or in other words, to assume an 60 65 "on" and "off" position.

While the spindle may be directly rotated by the operator, and while in certain fields of use this mode of operation may prove the most convenient, I have found it desirable where the switch is used in a portable handled tool, to provide means for this purpose of the sort illustrated in Fig. 1. Such illustrated means comprise a second spindle 21 centrally rotatably held within the handle 1 proper and carrying at its outer end a 75 knurled sleeve 22 partially inclosing said handle and providing a grip for the operator's use. Said spindle may be in effect regarded as a continuation of the switch spindle 8, the two being non-rotatably secured together, although electrically insulated from each other, so that the parts of the switch previously described, it will be observed, are entirely thus separated from the casing and the rest of the mechanism. 80 The insulating medium between the two spindles in the present instance is conveniently provided by means of a gear 23 of fiber or like material fixedly mounted on the inner end of the spindle 21 into which 85 gear the outer end of the switch-spindle extends and is there pinned, or keyed. Said gear 23 meshes with a pinion 24 rotatably mounted on the outer wall of the handle casing, to which gear, or rather to an extension 90 25 thereof, are eccentrically secured the ends of two tension springs 26 having their other ends secured to said casing at points 95 symmetrically disposed with respect to the axis of said pinion. A pawl 27 further engages the teeth of the gear 23 so as to permit movement thereof in the direction of the arrows, Figs. 2 and 4, but not in a reverse direction. The ratio of the gear and pinion is such that a one fourth turn of the 100 former, which as pointed out, will serve to move the switch from its "off" to "on" position, will also rotate the pinion into the position illustrated in Fig. 4, where the springs 26 are put under tension, and the 105 point of their attachment to the pinion-extension 25 is thrown just a trifle over center. Rotation of the gear to bring the parts into this position may be the result of several successive partial rotations, inasmuch as 110 the pawl will prevent reverse movement of the parts. With the parts in the position, however, of Fig. 4, the springs will continue the rotative movement of the pinion 24 and thus of the gear 23 and spindle 8, unless restrained by the operator's grasp on the sleeve 22 carried by the spindle 21. In other words, the moment he releases such sleeve, the springs will resume their normal position and by so doing will "snap" the switch 115 a second time, restoring the same to the original position from which it was started. Accordingly, not only does the operating mechanism for the switch provide a convenient means whereby the operator can con- 120 125 130

trol the latter without shifting his hand from the handle used in manipulating the tool, but the moment he releases his hold on the handle, whether through accident or 5 carelessness, the current is shut off and thus a large element of danger, especially in the handling of the more powerful tools of this type, is eliminated. It will be understood that where the tool is a drill the tool spindle 10 is geared down so that if the body of the tool is free from the operator's control while the tool itself is held fast, as by sticking in the work, such body will rotate at a considerable speed with attendant disastrous results.

15 Figs. 8 and 9 illustrate a simpler form of operating means for rotating the switch spindle, such means, however, being shown as incorporated in a handle of the kind hereinbefore referred to. A solid spindle 28 20 rotatably held within the handle, is here connected with the switch-spindle 8 and, as before, carries a sleeve 29 that incloses the handle proper so as to form a grip for the operator, both for the ordinary manipulation of the tool and for effecting rotation of 25 the switch-spindle. In order that the movement of the latter may be confined to the proper direction, a spring-pressed plunger 30 is transversely mounted in the spindle extension 28 and four notches 31 are provided 30 in the adjacent portion of the handle wall so as to be engaged by said plunger in each of the four positions which the spindle should successively assume, as the switch is moved "off" to "on" and "on" to "off." 35 The details of the switch are the same as before and need not be described in detail.

Other modes of applying the principle of 40 my invention may be employed instead of the one explained, change being made as regards the mechanism herein disclosed provided the means stated by any of the following claims or the equivalent of such stated means be employed.

45 I therefore particularly point out and distinctly claim as my invention:—

1. In a device of the character described, the combination of two spaced contacts; a movable piece adapted to bridge said contacts; tension means for effecting, and a catch for restraining, such movement; a 50 spring tending to hold said catch in its restraining position; and means adapted to render said tension means operative and 55 thereupon release said catch.

2. In a device of the character described, the combination of two spaced contacts; a rotatable piece adapted to bridge said contacts; a coil spring adapted, when wound up, 60 to effect rotation of said bridge piece; a catch adapted to restrain such rotation; a spring tending to hold said catch in its restraining position; and means adapted to wind up said spring and thereupon release 65 said catch.

3. In a device of the character described, the combination of a base of suitable material; two spaced contacts mounted thereon; a member rotatably mounted between said contacts; a piece carried by said member and 70 adapted to bridge said contacts, said piece being movable relatively to said member; and resilient means, interposed between said member and piece, adapted to press the latter against said contacts.

4. In a device of the character described, the combination of a base of suitable material; two spaced contacts mounted thereon; a member rotatably mounted between said contacts; a piece carried by said member and 75 adapted to bridge said contacts, said piece being movable relatively to said member; resilient means, interposed between said member and piece, adapted to press the latter against said contacts; a coil spring 80 adapted, when wound up, to effect rotation of said member, and thus of said bridge piece; a catch adapted to restrain such rotation; and means adapted to wind up said spring 85 and thereupon release said catch.

5. In a device of the character described, the combination of a base of suitable material; two spaced contacts mounted thereon; a member rotatably mounted between said contacts; a piece carried by said member and 90 adapted to bridge said contacts, said piece being movable relatively to said member; resilient means, interposed between said member and piece, adapted to press the latter against said contacts; a coil spring 95 adapted, when wound up, to effect rotation of said member, and thus of said bridge piece; a series of steps alternately corresponding with "on" and "off" positions of said piece; a reciprocal catch adapted to engage successive stops to restrain rotation of said member; and a spindle adapted to wind up said spring and thereupon reciprocate said catch to release the same.

6. In a device of the character described, the combination of a base of suitable material; two spaced contacts mounted thereon; a member rotatably mounted between said contacts; a piece carried by said member and 100 adapted to bridge said contacts, said piece being movable relatively to said member; resilient means, interposed between said member and piece, adapted to press the latter against said contacts; a series of stops alternately corresponding with "on" and "off" 105 positions of said piece; a reciprocal catch adapted to engage successive stops to restrain rotation of said member; a spindle provided with a cam adapted to reciprocate said catch to release the same; and a coil 110 spring connected at one end to said spindle and at the other to said member, whereby the latter is rotated when said catch is thus released.

7. In a device of the character described, 115

the combination of two spaced contacts; a movable piece adapted alternately to make and break contact with said contacts; means for moving said piece, including a spindle 5 rotatable in only one direction; and resilient means connected with said spindle, said resilient means being so disposed as to be under tension when said piece is in its "on" position, and being adapted, on release of 10 said spindle, to rotate said spindle and thereby move said piece to its "off" position.

8. In a device of the character described, the combination of two spaced contacts; a 15 movable piece adapted alternately to make and break contact with said contacts; means for moving said piece, including a spindle rotatable in only one direction; a pinion geared to said spindle; and a spring connected with said pinion and adapted to be 20 under tension when said piece is in its "on" position, and being adapted, on release of said spindle, to rotate said spindle and thereby move said piece to its "off" position.

25 9. In a device of the character described, the combination of two spaced contacts; a movable piece adapted alternately to make and break contact with said contacts; a coil spring adapted, when wound up, to effect rotation of said piece; a catch adapted to restrain such rotation; means adapted to wind 30

up said spring and thereupon release said catch, said means including a spindle rotatable in only one direction; and resilient means connected with said spindle, said resilient means being disposed so as to be under tension when said piece is in its "on" position, and being adapted, on release of said spindle, to rotate said spindle and thereby move said piece to its "off" position. 40

10. In a device of the character described, the combination of two spaced contacts; a rotatable piece adapted alternately to make and break contact with said contacts; a coil spring, adapted, when wound up, to effect 45 rotation of said piece; a catch adapted to restrain such rotation; means adapted to wind up said spring and thereupon release said catch, said means including a spindle rotatable in only one direction; a pinion 50 geared to said spindle; and a spring connected with said pinion and adapted to be under tension when said piece is in its "on" position, and being adapted, on release of said spindle, to rotate said spindle and thereby move said piece to its "off" position. 55

Signed by me this 6th day of February, 1911.

FRANKLIN SCHNEIDER.
